MASONIC HALL.

John Mc Arthur
Inventor

United States Patent Office.

JOHN McARTHUR, JR., OF PHILADELPHIA, PENNSYLVANIA.

Design No. 2,866, dated January 28, 1868.

DESIGN FOR A MASONIC HALL.

The Schedule referred to in these Letters Patent and making part of the same.

O ALL WHOM IT MAY CONCERN:

Be it known that I, JOHN McARTHUR, Jr., of the city of Philadelphia, county of Philadelphia, and State of Pennsylvania, have originated and designed a building for a "Masonic Hall," of which the following is a full, clear, and exact description, reference being had to the accompanying photographs, making a part of this specification, and showing a perspective view of the building.

The building is perpendicular, Gothic in style, three stories in height, and has a front of one hundred and fifty feet, and a depth of two hundred and fifty feet. The principal entrance is through a deep-recessed portal in the base of the great tower, which occupies the centre of the front, and terminates in a spire two hundred and thirty feet above the pavement. Each front is supported at the corners by richly-panelled octagonal towers, one on each corner. Between these the cell of the building is divided into bays by enriched buttresses pinnacled above the battlement-line, which is ninety-six feet from the pavement. The roofs are of slate, defended in the tops by a rich Gothic cast-iron railing.

Having thus described my invention, what I claim, and desire to secure by Letters Patent of the United States, is—

The design for a Masonic Hall herein set forth and described, and shown in the accompanying photographic view.

JOHN McARTHUR, JR.
